cember 17, 1936

6 Claims. (Cl. 199—68)

This invention relates to spacebands for matrix composing and type line casting machines, and constitutes an improvement in or modification of the devices shown in the specification of 8 U. S. A. patent application No. 119,967, filed on January 11, 1937.

As is well known in space wedges or spacebands of matrix composing and line casting machines at present in common use, comprise a stationary part and a displaceable part, the two parts being slidably interconnected and guided relatively to one another by a dovetail connection, the dovetailing being usually arranged on the smaller stationary part, while the longer, 15 movable part is provided with a corresponding dove-tail-shaped groove. As it is extremely difficult to provide the very thin stationary part with the dovetail shaped section, it has been proposed in the prior specification above referred 20 to to make the said section in two parts, one part carrying the ears and the other part the dovetailed guide. In the embodiment of the previous invention, described and illustrated in said prior specification, the ear carrying portion is pro- 25 vided with apertures, and with lugs adapted to co-operate with corresponding lugs located on that portion which carries the dovetail guide, the two parts, after mutual inter-engagement, being made fast to one another by the insertion of a 30 pin which is riveted. This arrangement operates quite satisfactorily but it has the disadvantage that the riveting of the inserted pin may cause a displacement of the parts which have been joined together, and moreover the parts 35 cannot be again separated for the purpose of conveniently cleaning them.

The object of the present invention is to overcome these disadvantages, and to this end there is contemplated a spaceband with a stationary 40 member likewise made in two parts, but wherein the assembly can be performed without any special means of attachment such as screws, rivets or the like, thus making it possible at all times to disassemble the parts.

45 According to the invention a spaceband for matrix composing and type line casting machines comprises relatively movable members, wherein one of said members is formed of parts having suitably shaped portions to fit together in the 50 assembled spaceband, and adapted to be detachably assembled to form one of said movable members.

In the accompanying drawing one constructional form of the invention is illustrated, and 55 in the said drawing:—

Figure 1 is a side elevation of an assembled spaceband according to the invention;

Figure 2 is the stationary part of the band shown by itself in a side elevation drawn to a larger scale; 5

Figure 3 is a section taken on the line 3—3 of Figure 2;

Figure 4 is a side elevation of the part by itself carrying the dovetailing, and

Figure 5 is a side elevation of Figure 2. 10

In carrying the invention into effect in one convenient manner, as shown in the accompanying drawing, a spaceband consists as customary of the movable long member *a* which is wedge shaped and carries on one side in the centre a 15 dovetail shaped longitudinal groove, the rear wall of the groove of which may be partly interrupted in known manner. The two sides which carry the dovetail groove on mutually opposed faces are therefore merely held together at their top 20 thin ends, and at the bottom by the connecting member *a*.

The stationary member is made in two parts one of which consists of the wedge shaped part *b* carrying in the customary manner the ears *c* 25 by means of which the spaceband is guided during its travel in the machine. The other part completing the stationary spaceband member carries the dovetail guide *e* and is constructed as a separate part. As will be seen more clearly in Figures 3 and 4 this part consists of two members *d* and *e* which are joined together or integral with one another and are dovetailed in cross section. The part *d* is approximately rectangular and in order to form the dovetailing its longitudinal edges are bevelled, the said part engaging in a corresponding open space in the part *b* which is bevelled in an opposing sense on the edges co-operating with the bevelled edges of the part *d*. The part *e* which engages the dovetailed groove of the movable part *a* is somewhat narrower than the plate *d* but is preferably made to project downwardly beyond the latter (see 30 Figures 2 and 4). The two parts *e* and *d* can be 35 made in one piece, or in two parts securely joined together by rivets or the like. 40

For the purpose of assembling the spaceband the parts *d*, *e* are inserted into the part *b* in the manner shown in Figures 2 and 3, and the 50 long movable part *a*, with its dovetail guide, is then slipped over the dovetail *e*. The parts *a* and *b* thereby become fast but are mutually displaceable in the longitudinal direction. The taking apart of the spaceband is effected without 55

any difficulty by sliding the long member *a* away from the dovetail *e*.

It should be understood that the invention is not restricted solely to the details of construction 5 of the form described above, which may be modified in various ways without departing from the scope of the invention. For instance, instead of assembling the part *b* and the plate *d* by means of dovetailed bevelling of the edges, any other 10 form of mutually positioning the parts, such as a prismatic arrangement, may be adopted. It is not necessary for the part *e* to project downwardly from the plate *d*, and if it does not project in the manner shown the assembly and location of 15 the plate *d* relatively to the part *b* may be effected by means of abutments or bevels on the top or bottom edges of the rectangular aperture of the member *b* and/or the plate *d*. The parts *b* and *d* are not necessarily rectangular, but may be 20 given any other preferred shape, as desired.

Having described my invention, I declare that what I claim and desire to secure by Letters Patent is:—

1. A spaceband for a matrix composing and 25 type line casting machine comprising relatively movable members, wherein one of said members is formed of parts having suitably shaped portions to be detachably assembled by interfitting engagement and being adapted to be held together by 30 their assembly with the other member to form the complete spaceband.

2. A spaceband for a matrix composing and type line casting machine comprising three parts 35 detachably connected, two of said parts being shaped to fit together and be movable, as a unit, relatively to the other part and being held together by their assembly with said other part to form the complete spaceband.

3. A spaceband for a matrix composing and 40 type line casting machine comprising a long

wedge member, having a dovetailed groove, a shorter wedge member, and a separate connecting piece associated with the shorter member by interfitting engagement therewith and having a dovetailed guide for engaging said dovetailed groove to hold said long and shorter wedge members in movable relation, said members and connecting piece being held together by their interfitting engagement with one another.

4. A spaceband according to claim 3, wherein 10 said shorter wedge member is apertured, said connecting piece extending through said aperture so that the dovetailed guide projects beyond one side of the shorter wedge member, said connecting piece being adapted to prevent removal of the 15 shorter wedge member laterally away from the longer wedge member when the spaceband is assembled.

5. A spaceband for a matrix composing and 20 type line casting machine comprising a long wedge member with a longitudinal dovetailed groove, a shorter wedge member having an aperture with bevelled edges, and a removable connecting piece having a dovetailed guide on one side adapted slidably to engage in said dovetailed 25 groove, said connecting piece being adapted to fit into said aperture and having bevelled edges corresponding to the bevelled edges of the aperture, and said bevelling of the edges being opposed to the bevelling of the dovetailed guide on the connecting piece.

6. A justifying spaceband including, in combination, a pair of relatively movable complementary wedge-shaped members presenting inner surfaces in bearing contact, and a removable connecting element having a tight fitting tongue and groove connection with one member and a sliding connection with the other member to hold the 35 members against facewise movement.
